[57] CLAIM

The ornamental design for a fan, as shown and described.

DESCRIPTION

FIG. 1 is a front view of a fan showing my new design;
 FIG. 2 is a rear view thereof;

FIG. 3 is a cross sectional view taken on line 3—3 of
 FIG. 1;

FIG. 4 is fragmentary elevational view taken along line
 4—4 of FIG. 1; and

FIG. 5 is a front view of a modified form of the fan
 shown in FIG. 1, the modification residing in the length
 of the fan blades.

FIG. 1

FIG. 3

FIG. 4

FIG. 2

FIG. 5
